Patented January 31, 1905.

UNITED STATES PATENT OFFICE.

FÉLICIEN BERTON-HOUEL, OF PARIS, FRANCE.

DESIGN FOR A MOTOR-CAR HORN.

SPECIFICATION forming part of Design No. 37,313, dated January 31, 1905.

Application filed April 11, 1904. Serial No. 202,689. Term of patent 7 years.

To all whom it may concern:

Be it known that I, FÉLICIEN BERTON-HOUEL, a citizen of the Republic of France, residing at Paris, France, have invented a new, 5 original, and ornamental Design for Motor-Car Horns, of which the following is a specification, reference being had to the accompanying drawings, forming a part thereof.

Figure 1 is a front elevation of a motor-car horn, showing my new design. Fig. 2 is a 10 plan view.

What I claim as new, and desire to secure by Letters Patent, is—

The ornamental design for a motor-car horn, as shown.

FÉLICIEN BERTON-HOUEL.
